UNITED STATES PATENT OFFICE.

THOMAS H. RIGGS MILLER, OF NEW YORK, N. Y., ASSIGNOR TO MYROPHONE COMPANY, INC., OF NEW YORK, N. Y.

SANITARY TELEPHONE ATTACHMENT.

1,140,996.

Specification of Letters Patent. Patented May 25, 1915.

Application filed October 22, 1914. Serial No. 863,033.

To all whom it may concern:

Be it known that I, THOMAS H. RIGGS MILLER, a subject of the King of Great Britain, and a resident of the city of New York, borough of Manhattan, in the county and State of New York, have invented a new and Improved Sanitary Telephone Attachment, of which the following is a full, clear, and exact description.

10 This invention relates to telephone appliances and deals more particularly with a sanitary attachment for transmitters.

The invention has for its general objects to improve and simplify the construction 15 of transmitter attachments of the character referred to so as to be reliable and efficient in use, comparatively simple and inexpensive to manufacture, and so designed as to be easily and quickly applied to the mouth- 20 piece of the transmitter and effectively retained when once applied.

A further object of the invention is the provision of a telephone transmitter having a novel arrangement of antiseptic holder 25 which, in addition to keeping the transmitter in a sanitary condition, conduces to the clearness of the sounds directed into the transmitter.

With such objects in view, and others 30 which will appear as the description proceeds, the invention comprises various novel features of construction and arrangement of parts which will be set forth with particularity in the following description and 35 claims appended hereto.

In the accompanying drawing, which 40 illustrates one embodiment of the invention, and wherein similar characters of reference indicate corresponding parts in all the views, Figure 1 is a central vertical section of the attachment applied to the mouthpiece of a telephone transmitter; Fig. 2 is a front view of the attachment; Fig. 3 is a sectional view of the attaching ring removed; and Fig. 4 45 is a sectional view of the antiseptic holder and sound clarifier.

Referring to the drawing, A designates 50 an ordinary telephone transmitter, to the mouthpiece 1 of which is applied the sanitary attachment B, which is of such a nature that it can be easily and quickly applied without the use of tools and without altering the form of the mouthpiece, so that the attachment is capable of universal application.

The attachment comprises a metallic cup-like body or shell 2, which, in its front surface, is provided with a central opening 3, and around the edge of the front plate is an annular rim 4 that is provided with an internally-extending annular flange 5 at its rear. Within the shell or body 2 is a holder for the antiseptic material. This holder comprises two circular pieces of wire gauze 6 and 7 suitably bound together at their periphery, as by a clamping ring 8 which is spun or otherwise formed around the pieces 6 and 7, as a binding. The wire mesh piece 7 is bowed away from the other piece 6, and between the two is a lump or cake 9 of suitable antiseptic material which is of such size that considerable space is provided around it for the passage of sounds into the transmitter. A rubber or other elastic ring 10 is disposed behind the antiseptic holder 70 and presses the same firmly against the front of the shell so that there is no danger of rattling. This ring is subjected to compression by the turning in of the flange 5 of the shell, and thereby the periphery of this ring 10 is 75 tightly held in place. This ring in cross-section tapers inwardly to form a thin annular lip 11, and the internal diameter of the ring is considerably smaller than the diameter of the flared end of the mouthpiece 80 1 of the telephone transmitter, so that the said mouthpiece can be tightly engaged by the annular lip 11 when the mouthpiece is inserted in the opening of the ring 10. Since the ring is made of rubber the lip 11 will 85 readily yield to permit the mouthpiece to be inserted, and when inserted the attachment is tightly held in place without being liable to rattle and cause a confusion of sounds in the transmitter. It will thus be seen that 90 the ring 10 performs two functions, namely, that of tightly clamping in the shell the holder of the antiseptic material, and of firmly holding the attachment on the transmitter.

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown 100 105 110

is merely illustrative and that such changes may be made when desired as are within the scope of the appended claims.

Having thus described my invention, I claim as new and desire to secure by Letters Patent:

1. A sanitary attachment for telephone transmitters comprising a shell having an opening, a holder for sanitary material disposed in the shell, and a resilient ring clamped at its outer edge in the shell and firmly securing the said holder in place, said ring being formed with an internal yielding annular lip for engagement around the mouthpiece of the transmitter and forming the sole means for retaining the attachment on the said mouthpiece.
2. A sanitary attachment for telephone transmitters comprising a shell having an opening, a holder for sanitary material disposed in the shell, and a resilient ring clamped in the shell and firmly securing the said holder in place, said ring being formed with an internal yielding annular lip for engagement around the mouthpiece of the transmitter, said holder comprising two

wire gauze pieces bound together at their periphery and spaced apart at the middle, and antiseptic material confined between the said gauze pieces at the middle.

3. A telephone attachment comprising a shell consisting of a front plate having an opening and a peripheral rim, an antiseptic holder disposed within the shell, and a ring arranged within the shell and engaging the periphery of the holder, said ring being of resilient material and tapering inwardly to form a yielding internal annular lip for externally engaging the mouthpiece of a transmitter, said rim of the shell being provided with an internal annular flange at its rear, whereby the periphery of the ring is held under compression to clamp the antiseptic holder tightly against the front plate of the shell.

In testimony whereof I have signed my name to this specification in the presence of two subscribing witnesses.

THOMAS H. RIGGS MILLER.
